ABSTRACT OF THE DISCLOSURE

A gas turbine by-pass engine has a compressor means, a combustion means and a turbine means, a rotatable main fan extends completely across the by-pass duct and a secondary fan is positioned upstream of the main fan and extends only partially across the by-pass duct. The secondary fan is driven by the turbine means and the main fan is mounted on a casing having blades driven by the compressor means.

This invention relates to gas turbine by-pass engines in which a fan is mounted in the by-pass duct of the engine.

According to the present invention there is provided a gas turbine by-pass engine having compressor means, combustion means and turbine means, a rotatable main fan extending completely across the by-pass duct and a rotatable secondary fan positioned upstream of the main fan and extending only partially across the by-pass duct, the secondary fan being driven by the turbine means.

Preferably the tip speed of both the main fan and secondary fan is arranged to give a blade relative inlet Mach number always less than unity. The main fan is arranged to be mounted on a casing having blades driven by the compressor means.

The invention will now be more particularly described with reference to the accompanying drawing which shows a diagrammatic representation of one form of gas turbine by-pass engine according to the present invention.

In the drawing, a gas turbine by-pass engine consists of compressor means 10, combustion means 12 and turbine means 14.

The compressor means 10 has a multistage compressor 16 driven by a turbine 18 through a shaft 20 and a conventional high pressure compressor 22 driven by a turbine 24 through a shaft 26. A main fan 28 extends completely across the by-pass duct 30 of the engine and is mounted on a rotatable casing 32 which has rows of stator blades (which remove energy from the air and therefore act as turbine blades) positioned between rows of compressor blades 36 on the low pressure compressor 16. The main fan 28 is in the form of a spoked wheel having a hub, a number of radial blades or spokes connected to a splitter ring 38 and a number of fan blades attached to the splitter ring. A secondary fan 40 is mounted upstream of the main fan and the blades of the fan extend only as far as the splitter ring of the main fan. The secondary fan 40 is mounted on a shaft 42 which is driven by a turbine 44. The shaft 20 and the casing 32 rotate in the same direction as shown by the arrows A and the remaining shafts 26 and 42 can rotate either in the same or the opposite direction both to the shaft 20 and to each other.

The torque required to drive the main fan 28 is transmitted aerodynamically through the low pressure compressor stators which are in fact the blades 34 acting as turbine blades. Sufficient torque is provided by the turbine

2

18 through the shaft 20 and hence the low pressure compressor blades 36, to drive the compressor stators and to provide the required net pressure rise over the compressor 16.

5 Both the main fan and the secondary fan are arranged to operate at sufficiently low tip speeds to ensure that the blade tip relative inlet flow Mach numbers are less than unity. This arrangement avoids undesirable tone noise which is associated with blade relative inlet flow Mach numbers of greater than unity.

A principal difficulty with fans of low hub/tip ratio, as in the case of a conventional high by-pass ratio engine is that the tip runs faster than necessary for maximum efficiency if the root is to provide a satisfactory pressure rise. 15 The provision of the secondary fan 40 both enables a satisfactory pressure rise to be obtained at the root of the main fan and the intake to compressor 16 to allow the tip speed of the main fan to be reduced, thus giving a reduced main fan white noise level.

20 In comparison with a conventional front fan three shaft engine of high by-pass ratio in which a low fan tip speed is required the present arrangement offers a number of advantages. A lower number of turbine stages is required; this is because the torque required to drive the low speed 25 main fan 28 is transmitted aerodynamically through the stators 34 from the high speed blade rows 36; these are supplied with sufficient torque by the high speed turbine 18 to drive the low speed main fan 28 and to provide the required pressure rise over the low pressure compressor 16; 30 e.g. a high by-pass ratio fan engine having eleven turbine stages can be reduced to an engine having five turbine stages. The secondary fan 40 produces the pressure rise required over the inner portion of the by-pass duct in order that the torque required by the main fan balances the 35 torque transmitted by the stators 34. The secondary fan requires a small amount of torque which is produced by the moderately loaded turbine 44. This ensures a sufficiently low overall turbine noise level.

40 A higher compression ratio of the by-pass flow can be obtained and this is due to the presence of the secondary fan which reduces the whirl angle of the flow onto a ring of outlet guide vanes 46 in the region of the roots of the guide vanes, thus relieving the high outlet guide vane root diffusion loading associated with conventional low tip speed front fan engine design.

We claim:

1. A gas turbine engine having a by-pass duct and comprising:

50 compressor means, combustion means and turbine means in flow series; a rotatable main fan extending completely across said by-pass duct; a rotatable secondary fan extending only partially across said by-pass duct and rotatable within an annular splitter secured to said main fan, said compressor means having a high pressure and a low pressure compressor, said low pressure compressor having a rotatable casing to which said main fan is secured and is thereby arranged to be driven by said low pressure compressor, said turbine means having a high pressure, an intermediate pressure and a low pressure stage, said high pressure stage being arranged to drive said high pressure compressor by means of a first shaft, said intermediate pressure stage being arranged to drive said low pressure compressor by means of a second shaft and said low pressure stage being arranged to drive said secondary fan by means of a third shaft.
